PICKER STICK CHECK STRAP

Frank B. Wakefield, Auburn, Maine

Application September 5, 1947, Serial No. 772,321

2 Claims. (Cl. 154—46)

1

This invention relates to a picker stick check strap.

The object of the invention is to provide a novel and more durable picker stick check strap than others now upon the market of which I am aware, and one which will maintain its useful life for relatively long periods of time.

With this general object in view and such others as may hereinafter appear, the invention consists of the picker stick check strap herein-after described and particularly described in the claims at the end of this specification.

In the drawings illustrating the preferred embodiment of the invention, Fig. 1 is a plan view and Fig. 2 is a side elevation of the preferred form of picker stick check strap embodying the invention, Figs. 3 and 4 are views similar to Figs. 1 and 2 illustrating an endless picker stick strap embodying the invention, Fig. 5 is a side elevation of the picker stick strap shown in Fig. 1 prior to its assembly in a loom and Fig. 6 is a cross sectional view taken on line 6—6 of Fig. 5.

In general the invention contemplates the provision of a picker stick check strap which is adapted for use upon the loom to check the movement of the picker stick in both directions. Prior to the present invention picker stick check straps have been made of leather, either single or double ply, and also of various composition materials including rubberized textile belting and the like.

In the operation of the loom when the picker stick is being checked in its movements after throwing or receiving the shuttle the picker stick check strap is subjected to the combined effect of shock and heavy strain. The shock occurs upon impact of the picker stick with the strap and the stress and the strain result from the power utilized in the operation of the picker stick in throwing the shuttle and also in receiving same.

In attempting to find materials which would possess useful lives beyond those of the ordinary leather check straps and treated textile check straps hereinbefore used, I have discovered that a picker stick check strap 10 may be produced which will out-wear all other picker stick check straps of which I am aware, by constructing the strap of a multi-ply construction wherein the inside ply 12 is made of grain leather which is tanned by a combination tanning process to produce a combination tanned leather as is well known in the art of tanning leather, such combination tanned leather being tanned by both combined chrome and vegetable tanning process. The grain leather strap forming the inner ply 12 is 55 days which may vary from one to several days

2

then buffed to remove the calendered surface for a purpose to be described. The outer ply 14 is made of a tough tanned leather, having high tensile strength, and in practice I have found satisfactory results may be secured utilizing a combination tanned leather having a calendered, dense, hard outer surface, and a non-calendered inner surface.

In producing the check strap shown in Fig. 1, 10 I prefer to utilize a layer 16 of water-proof cement for uniting the outer and inner plies. Such a cement may be obtained which is flexible and heat-resistant. I have experienced satisfactory results using the commercially obtainable heat resistant water-proof cements, preferably embodying a cellulose or Celluloid base, but it is to be understood that other known heat-resisting water-proof cements which are capable of firmly uniting leather surfaces may be used if desired. 15 20 Most of such commercial waterproof cements comprise Celluloid cut with a solvent such as acetone. The outer and inner leather plies are united together under pressure either with or without heat, utilizing such a flexible waterproof heat-resistant cement, and preferably the plies are united so that the inner surface of the inner ply comprises the surface of the combination tanned grain leather which has been buffed, and the outer or upper surface of the outer ply comprises the hard, dense, but flexible, calendered surface of the combination tanned grain leather above referred to.

After the laminated strap has been thus produced, the next step in the process of producing the improved check strap involves the impregnation of the inner ply, and preferably both the inner and outer plies, with a non-drying oil and preferably a neat's-foot oil composition embodying a major portion of neat's-foot oil and a minor portion of wax, such as paraffin, and a diluent in a small amount. In practice it is preferred to immerse the laminated straps in such an oil bath for a period of from 8 minutes to 12 minutes although the time of immersion will depend upon the gravity and density of the leather, and in any event sufficient time should be permitted for the immersion so that the entire body of the laminated structure will be well impregnated. Other methods of impregnation may be employed if desired. Thereafter it is preferred that the impregnated straps be seasoned or mulled, and accordingly it is preferred to pile them in a moderately warm room for a period of 45 50 55 days which may vary from one to several days

after which the straps are ready for shipment and use.

From the description thus far it will be observed that the present laminated structure of leather check strap embodies an outer leather ply which possesses high tensile strength as well as flexibility and durability. The inner ply while possessing strength and durability does not possess the high tensile strength of the outer strap and is of a relatively porous and yieldable cushioning nature such that in use under the impact of the picker stick the strap yields and compresses slightly, minimizing the effect of the shock. The interposed layer of water-proof flexible heat-resisting cement connecting the yieldable inner or cushion member of the laminated structure to the outer more firm and strong tensile ply serves to transmit to the outer ply the strain produced by impact of the picker stick with the cushioning inner ply. The outer ply being relatively non-yieldable holds the structure in a firm position off-setting any permanent elongation and maintaining the check strap in the desired condition for effective operations for relatively long periods of time. The oil impregnant serves a most useful purpose not only in preserving the leather in the desired yieldable condition but also in lubricating the surface of the inner ply in its contact with the picker stick. This reduces to a minimum the burning effect produced by the friction between the picker stick and the check strap and further preserves the leather in a strong and durable condition from the deleterious effects of the high humidity now used in mills. In addition the complete impregnation of the entire check strap imparts an added degree of flexibility to both the inner and outer plies thus contributing to the long life of the check strap.

The utility of the present strap may be measured in some degree by experience with prior straps of oak tanned leather which under the conditions of high humidity of the present day mill last anywhere from two weeks to a month. Applicant's experience in connection with the present strap indicates a duration of upwards of six months under comparable conditions.

The present invention may be embodied in a picker stick check strap of the linear type such as is illustrated in Figs. 1, 2 and 5, preferably having the usual slots therein through which the usual fastening means may be extended to secure the strap in operative position with the free ends thereof in overlapping relation as shown in Figs. 1 and 2. In addition the invention may if desired be embodied in a picker stick check strap of the endless type as illustrated in Figs. 3 and 4, wherein the free ends of the strap are united by heat-resisting water-proof adhesive, at 20 or in other known manner. Such an endless check strap may be secured in the loom by any of the known holders now commonly employed.

In recapitulation, it will be observed that because of the highly humid atmospheric conditions of the present day mills under which the picker stick check straps are used, and because of the severe shocks and strains to which the same are subjected in present day high speed looms, the extension of the useful life of check straps and the reduction in wear on the picker stick are extremely important items in the expense of the loom upkeep.

While many attempts have heretofore been made to attain these results, none so far as I am aware have been successful. By the cooperation

of the outer ply of high tensile leather, for maintaining the shape, dimensions and resisting the strains, the inner ply of cushioning leather for absorbing the shock, the waterproof cement layer for transmitting strains to the outer ply, and the oil impregnation of the inner ply to reduce to a minimum the burning effect upon the check strap produced by the friction between the picker stick and the surface of the cushioning inner layer, I have produced a check strap which experience seems to indicate attains the desired results. The prior straps embodying oak tanned leather fail principally due to the burning of the leather, developing cracks under the heating effect developed from the friction between the picker stick and the strap. The porosity of the inner leather ply of the present strap serves as a reservoir for sufficient oil impregnant so that the surface thereof is maintained lubricated during the use 20 of the strap, thus reducing to a minimum the aforesaid friction and the heat developed.

While it is preferred to embody the invention in a two ply check strap, it is not desired to limit the invention thereto.

Having thus described the invention, what is claimed is:

1. A flexible, shock absorbing, picker stick check strap for looms, comprising: a laminated leather strap having an outer ply and an inner 30 ply, both plies being of substantial thickness, said outer ply comprising a strap of tough, dense, calendered tanned leather characterized by high tensile strength and serving to prevent undue stretching of the laminated leather strap under the strain set up in checking the movement of a loom picker stick, said inner ply comprising a strap of a highly porous compressible tanned grain leather, a layer of cement between said plies permanently bonding the inner ply to the 40 outer ply to form a unitary structure, said inner ply being impregnated with a substantial body of oil of a non-drying nature distributed throughout the interstices of the inner ply and forming in effect a lubricant reservoir from which said oil 45 can be readily expressed through the pores of said inner ply to the inner surface thereof by a blow from a picker stick, the substantial thickness, porosity, and compressibility of the inner ply enabling it to yield and be compressed substantially upon impact by the picker stick to cushion the shock of the picker stick on the check strap and to reduce the strain transmitted through the bonding cement to the outer ply, the impact of the picker stick automatically expressing oil from the porous inner ply onto the inner surface thereof to provide a sufficient oil film between the inner surface of the inner ply and the surface of the picker stick which engages therewith to reduce to a minimum the development of frictional heat therebetween when in use, thereby preventing burning of the check strap and contributing to the long life thereof.

2. A flexible, shock absorbing picker stick check strap for looms, comprising: a laminated leather 55 strap having an outer ply and an inner ply, both plies being of substantial thickness, said outer ply comprising a strap of tough, dense, calendered tanned leather characterized by high tensile strength and serving to prevent undue stretching 60 of the laminated leather strap under the strain set up in checking the movement of a loom picker stick, said inner ply comprising a strap of highly porous compressible tanned grain leather having the calendered inner surface thereof removed 65 to impart porosity thereto, a layer of cement be-

tween said plies permanently bonding said inner ply to said outer ply to form a unitary structure, said inner ply being impregnated with a substantial body of oil of a non-drying nature distributed throughout the interstices thereof and forming in effect a lubricant reservoir from which oil can be readily expressed through the pores of said inner ply to the inner surface thereof by a blow from a picker stick, the substantial thickness, porosity, and compressibility of the inner ply enabling it to yield and be compressed substantially upon impact engagement by the picker stick to cushion the shock of the picker stick on the check strap and to reduce the strain transmitted through the bonding cement to the outer ply, the impact of the picker stick automatically expressing oil from the porous inner ply onto the inner surface

5
thereof to provide a sufficient oil film between the inner surface of the inner ply and the surface of the picker stick which engages therewith to reduce to a minimum the development of frictional heat therebetween when in use, thereby preventing burning of the check strap and contributing to the long life thereof.
